UNITED STATES PATENT OFFICE.

PHILIP W. HUTTON, OF CHICAGO, AND EDWARD F. WORST, OF LOCKPORT, ILLINOIS.

DRAWING-BOARD SUPPORT.

1,163,755.

Specification of Letters Patent. Patented Dec. 14, 1915.

Application filed January 19, 1914. Serial No. 813,050.

To all whom it may concern:

Be it known that we, PHILIP W. HUTTON, residing at Chicago, in the county of Cook and State of Illinois, and EDWARD F. WORST, residing at Lockport, in the county of Will and State of Illinois, both citizens of the United States, have invented a certain new and useful Improvement in Drawing-Board Supports, of which the following is a specification.

Our invention relates to supports for drawing boards and similar objects.

The device is of special advantage in schools in which manual training is taught. In schools of this character the course includes both shop work and drawing and for the shop work a work bench is, of course, required. Such benches are invariably furnished with a vise of some kind. It is not always practical to devote a special room or rooms for class work in drawing and yet the work benches in the shops cannot well be used as drawing tables for reasons obvious to those familiar with work of manual training schools.

One of the objects of our invention is to provide means whereby it will become practical to use the same room for both shop work and drawing.

With this and other desiderata in view it is our purpose, more specifically, to provide a drawing board support which may be held in a work bench vise; second, to provide a drawing board and support the parts whereof may be readily assembled and disassembled so that the drawing apparatus may be stored when not in use.

As contributing to these general objects, it is our purpose to provide certain details of construction more specifically pointed out in the following description and claims.

We obtain our objects by the construction illustrated in the accompanying drawings in which—

Figure 1 is a side elevation partly in section showing the parts mounted in a vise. Fig. 2 is a rear elevation of the parts shown in Fig. 1. Fig. 3 is a plan section on the line 3—3, Fig. 1. Fig. 4 is a sectional elevation on the line 4—4, Fig. 1. Fig. 5 is a detail showing the manner of supporting the side bars on the trunnions. Fig. 6 is a perspective view of the support showing the manner in which the turn button engages the type of cleat shown in Fig. 9. Fig. 7 is a perspective of the upper end of the stand-

ard. Fig. 8 shows the upper end of the standard with the turn button removed. Fig. 9 is a perspective of one form of cleat with which the drawing board may be provided. Fig. 10 is a front to rear sectional elevation showing the board equipped with the type of cleat shown in Fig. 9 and Fig. 11 shows a modified form of cleat.

Similar numerals refer to similar parts throughout the several views.

In the form selected to illustrate the invention the standard 1 is adapted to be secured in a work bench vise A illustrated at the lower part of Figs. 1 and 2. This vise may be of different forms and need not be described in detail. The standard widens out at the upper end to give stability and is provided with two laterally projecting trunnions 2, 2. These trunnions are preferably supported in a block 3 secured to the back of the standard, as best shown in Fig. 7.

The standard supports a frame which in the present preferred form consists of two parallel side bars 4, 4, fastened together by two cross bars 5, 6. By preference the upper surface of the front bar 5 should come flush with the upper surface of the side bars while the rear cross bar should be slightly elevated as shown. Stops 7 are formed at the forward end of the side bars for limiting the forward movement of the board.

Drawing boards are usually all pretty much the same in general construction although slight variations may occur. A well known type of board is shown in Figs. 1 to 4, and in this type the board proper 8 has marginal side strips 9, 9, of a thickness greater than that of the rest of the board. These engage the ends of the rear cross bar 6 and prevent the board from slipping laterally. In this type also an under pocket 10 is formed at the front of the board by a bottom strip 11, the purpose of the pocket being to afford a receptacle for the triangles or other tools or instruments used by the student. In our device the upper edge of this bottom strip is engaged by the nose 12^a of a turn button 12 which is secured by a screw or other suitable pivot to the upper end of the standard. In the best form, a shoulder 12^b is formed on the underside of the turn button somewhat to the rear of the point of the nose and this acts as a stop for limiting the rearward movement of the board when the parts are assembled, as

shown for example in Figs. 1 and 3. By referring to Fig. 1 it will be evident that when the turn button is in acting position (in which condition it lies with its longest dimension extending from front to rear) the board is effectually prevented from moving in any direction. The nose of the button overlies strip 11 and thus prevents the board from rising. The stop 7 prevents the board from moving forward while the shoulder 12^b prevents the board from moving backward. The side strips 9, engaging the ends of the rear cross bar 6, prevent the board from moving laterally. Thus the board is secure in its position. It is desirable that the under surface of the nose 12^a should be slightly beveled so as to produce a clamping action upon strip 11 to hold it down with some force.

20 The supporting frame 4, 5, 6 is removable from the standard, and the manner of mounting the frame upon the standard constitutes one of the important characteristics of our invention. It will now be described:

25 Vertical slots 4^a are formed at the bottom of the side bars 4 approximately midway between the ends of the bars. The slots are located somewhat to the rear of the actual center, in the preferred design, with the result that the frame normally tends to tilt forward and cause the side bars 4 to rest upon the stops or shoulders 1^a formed at the side of the standard, as best shown in Figs. 6 and 7. By preference slots 4^a are 30 narrower at the mouth than at the inner end and the trunnions 2 are horizontally flattened with the result that the slots will receive the trunnions only when the frame is held in vertical position, and when the 35 frame is afterward rotated to horizontal position it cannot be lifted off the trunnions. The consequence is that when the parts are in the position of use the frame and the standard are interlocked, the principle being clearly illustrated in Fig. 5 of the drawings. In the best construction the side bars 4 not only rest upon the shoulders 1^a but also lie against the ends of the standard and thus prevent the frame from moving laterally. This is not essential, however, 40 for in the best design heads 2^a are formed at the ends of the trunnions and these would be sufficient to hold the frame against lateral movement.

45 By reference to the drawings it will be seen that the trunnions are located to the rear of the standard while the point of engagement of the turn button with the strip 11 is in front of the standard; consequently when the button is in action it holds the frame and superposed drawing board against rotation. In our construction we 50 relieve the pivot pin 13 of undue strain in resisting this turning movement by so proportioning the parts that when the button is

acting, its rear end will rest upon the block 3. By referring to Fig. 1, for example, it will be seen that as a result of this arrangement, if pressure be exerted upon the board to urge it to tilt backward (in a clockwise direction, Fig. 1) there would, practically speaking, be simply a tensional strain upon the pivot, and there would be little, if any, tendency to bend it. As the resistance to tensional strain in the pivot is much greater than its resistance to bending it is evident that a comparatively small pivot may be safely used.

In the preferred form means are provided for preventing the button from being rotated too far when turning from non acting to acting position. The means in question comprise a shoulder 12^c formed on the bottom of the button behind the pivot, this shoulder abutting the back of the standard when the button has reached acting position, as shown in Fig. 7, and elsewhere. A recess 1^b is cut in the top of the standard at one side of the pivot, as best shown in Figs. 7 and 8, this recess accommodating the shoulder 12^c when the button is turned to non acting position.

The operation and coaction of the various parts will be obvious from the foregoing description. When a student wishes to set up his board he first takes the standard 1 and secures it in the vise A at the elevation which will best suit him. He then takes the frame 4, 5, 6 and, bringing it to vertical position behind the standard, passes the slotted bars 4 over the trunnions 2. He then rotates the frame down until the bars rest upon the shoulders 1^a of the standard, where the frame will temporarily rest under the action of gravity. He then lays the board upon the frame, bringing the front edge into engagement with the stop 7 and the side strips 9 into engagement with the ends of the rear cross bar 6. He then turns the nose of the button forward to acting position, as shown for example in Fig. 1, whereupon all of the parts, to-wit, the board, the frame and the standard will be securely locked together and held in the proper relative positions. When he has finished using the board all he has to do is to turn the button to non acting position and loosen the vise, whereupon the board, frame and standard may be readily disassembled and put away. As the parts are all approximately flat and somewhat of the same size they occupy but small space when stored.

It is not essential that the board be provided with a pocket of the precise form shown in Fig. 1 and elsewhere. Instead of the pocket a simple recessed cleat marked 15 in Figs. 6, 9 and 10 may be employed. By making the cleat thick enough and long enough, as suggested, it may, at its ends, engage the inside faces of the parallel bars 4 130

and thus prevent the board from moving laterally. If desired the cleat may assume the form shown at 16, Fig. 11, the cleat being recessed, as before, for the reception of the 5 nose of the turn button but being of somewhat different shape.

Having thus described our invention, what we claim as new and desire to secure by Letters Patent, is:

10 1. In combination, a drawing board having a recess formed in the underside thereof, a standard, a frame pivotally supported upon said standard and adapted to support said board, and a holding element pivoted to said standard and adapted to enter the recess in said drawing board for locking the drawing board, frame and standard in fixed 15 relative positions.

2. In combination, a standard having a bearing surface thereon, a frame pivoted to said standard at one side of said bearing surface, a catch fastened to said standard, and a drawing board resting upon said frame, said catch being adapted to overlie a 25 portion of said board at a point on the opposite side of the said bearing surface from the point where the frame is pivoted to the support, said catch thus holding the board down on the frame and the frame down on 30 said bearing surface.

3. In combination, a standard, a frame pivoted to said standard, a drawing board resting upon said frame and having a recess in its under side, said recess and the frame 35 pivot being on opposite sides of the standard, and a catch movably fastened to said standard and entering said recess when the board is in acting position to hold down that portion of the board and prevent rotation of the board and frame about the frame 40 pivot.

4. In combination, a standard, a frame pivoted thereon, a shoulder on said standard coöoperating with the frame pivot for holding said frame in normal position of use, a drawing board on said frame, said drawing board having a recess on the underside, a button, a pivot holding said button to said standard, the end of the button 50 entering the recess in the board for holding the frame down on the shoulder of the standard, and a rest for supporting the rear end of the button when the latter is in acting

position, to thereby relieve the button pivot of bending strain.

55

5. In combination, a standard, a block secured to the back thereof, trunnions on said standard, a frame detachably supported upon said trunnions, shoulders on said standard for engaging said frame at a point 60 in front of the trunnions, and means for holding said frame down upon said shoulder, said means including a drawing board located on the frame and a catch movably mounted upon said standard, said catch being adapted to engage said drawing board 65 substantially as described.

6. In combination, a standard, a frame pivoted thereon at a point behind the standard, a shoulder on said standard at a point 70 in front of the frame pivot for holding the frame approximately horizontal, means for preventing lateral movement of the frame, a drawing board upon said frame, a turn button engaging said board and exerting 75 downward pressure thereon at a point in front of the frame pivot to thereby hold the board down on the frame and the frame seated upon the shoulder of the standard.

7. In combination, a standard, a frame 80 pivoted thereon at a point behind the standard, a shoulder on the standard at a point in front of the frame pivot for holding the frame approximately horizontal, side bars straddling said standard for preventing lateral movement of the frame, a board on 85 the frame, a strip fastened to the underside of the board, a turn button on said standard adapted to engage the strip on the drawing board for holding the board down on the 90 frame and the frame seated upon the shoulder of the standard, stops on said frame for limiting the forward movement of the board, a shoulder on said turn button for holding the board in engagement with the 95 stops on the frame, and a rest for the rear end of the turn button when the latter is in acting position.

In witness whereof we have hereunto subscribed our names in the presence of two 100 witnesses.

PHILIP W. HUTTON.
EDWARD F. WORST.
